UNITED STATES PATENT OFFICE.

JAMES CHANDLER, OF NEW YORK, N. Y., ASSIGNOR OF ONE-HALF TO
CHARLES NELSON, OF SAME PLACE.

DESIGN FOR A GAS-FLAME SPREADER.

SPECIFICATION forming part of Design No. 32,789, dated June 5, 1900.

Application filed April 30, 1900. Serial No. 15,014. Term of patent 3½ years.

To all whom it may concern:

Be it known that I, JAMES CHANDLER, a subject of the Queen of Great Britain, and a resident of New York city, county and State of 5 New York, have invented and produced a new and original Design for a Gas-Flame Spreader, of which the following is a specification.

My design for a gas-flame spreader is represented in the accompanying drawings, in 10 which—

Figure 1 is a side elevation of the spreader. Fig. 2 is an elevation as seen looking in the direction indicated by the arrow at Fig. 1, and Fig. 3 is a top view.

15 The side view presents a parallelogram of greater lateral than vertical breadth, having the convex middle surface *a* merging in the outward or frontward turned cylindrical rolls *b* and *c* of the respective extremities of the 20 parallelogram. From the roll *c* rises an upright member *e*, terminating in a right-angular extension *f*, reaching forward over the part *a* and terminating at or about a vertical central line of said part *a*, and the lower end 25 of roll *c* has a pendent boss *g*. The eleva-

tion in Fig. 2 presents another parallelogram *h* of about equal lateral and vertical dimensions, with the lateral borders merging in rolls *c*, respectively. From each roll *c* rises an upright member *e*, terminating in an angular extension *i*, oppositely directed, respectively, and between these oppositely-directed extensions is seen a member *j*.

In the plan view, Fig. 3, the upper edges of two parallelograms *a* and their terminal end 35 rolls *b* and *c*, also the upper edge of the parallelogram *h*, also the lateral extension *i*, are seen, and this view also shows the member *j* joined to laterally-curved extremities of extensions *i*.

40 What I claim is—

The design for a gas-flame spreader as herein shown and described.

Signed by me at New York, N. Y., this 28th day of April, 1900.

JAMES CHANDLER.
